UNITED STATES PATENT OFFICE

2,381,726

LIGHTER FOR CIGARETTES AND THE LIKE

Lincoln K. Davis, Brockton, Mass.

Application July 22, 1941, Serial No. 403,476

9 Claims. (Cl. 219—32)

My invention relates to electrically actuated tobacco lighters of the type commonly used on automobiles. It concerns especially the type designated as "cordless" or "wireless," wherein the body of the lighter, carrying an incandescent igniting element, may be removed for use from a fixed holder, which is usually attached to the dash of the automobile, and which has provision for making the electrical connections necessary for the energizing of the igniting element, manually or semi-automatically. The term "cordless" when used herein is to be understood to refer to this type.

A principal object of the invention is to ensure engagement of the end of a cigarette with the igniting element, without visual attention on the part of the user; another object is to provide for improved ventilation of the igniting element, to promote quick and efficient lighting; a third object is to prevent particles of burning tobacco from escaping when lighting a cigarette; a fourth object is to provide access to the igniting element from two directions, whereby the lighter may be used either as an ordinary cordless, or as the type herein disclosed, which may be termed "self-engaging"; another object is the provision of a convenient cigarette extinguisher.

In a preferred form of my device I attain the objects set forth by making the lighter body of plug form, with an axial hole through it adapted to receive a cigarette or cigar. One end is formed into a knob, for handling, while the other end carries the igniting element, which is of wire, preferably, and is disposed across the axial hole. The user inserts a cigarette in the hole and pushes it in until it is stopped by the igniting element, which is then energized until it is properly incandescent. Then the lighter body, together with the inserted cigarette, is removed from its holder, and the protruding end of the cigarette is placed between the lips. One puff invariably is sufficient to light it thoroughly, after which the lighter body is withdrawn from the cigarette and replaced in the holder, or passed to another user.

My invention also consists in certain new and original features of construction and combinations of parts hereinafter set forth and claimed.

Although the novel features which are believed to be characteristic of my invention will be particularly pointed out in the claims appended hereto, the invention itself, as to its objects and advantages, and the manner in which it may be carried out, may be better understood by referring to the following description taken

in connection with the accompanying drawing forming a part thereof, in which

Fig. 1 shows a longitudinal sectional view of one form of my lighter and its holder.

Fig. 2 is an end view of the igniting head.

Figs. 3 and 4 are modified forms of heater element; and

Fig. 5 is a longitudinal sectional view of a modified form of lighter having a thermostatic release, and associated draft-producing apparatus for lighting a cigarette automatically.

In the following description and in the claims, various details will be identified by specific names for convenience, but they are intended to be as generic in their application as the art will permit.

Like reference characters denote like parts in the several figures of the drawing.

In the drawing accompanying and forming part of this specification, certain specific disclosure of the invention is made for purposes of explanation, but it will be understood that the details may be modified in various respects without departure from the broad aspect of my invention.

Referring to Figs. 1 and 2, the lighter body 1 is shown in place in its holder 2, which is illustrated as held to an automobile dash 3 by a retaining washer 4. Body 1 comprises a knob 5, which may be of any desired suitable material, threaded to an insulating cylinder 6, which in turn is threaded to an igniting head 7, which consists principally of a metal annulus 8, a ferrule-like cup 9, and an igniting element 10. One end of the last named, which is preferably of flat nichrome wire, is welded to tab 11 of metal washer 12, which is electrically connected to, and also held in place by, the eyelet portion 13 of annulus 8, which is flanged over in assembly. The other end of igniting element 10 is welded to the inside of cup 9. Mica washers 14 and 15 serve to isolate cup 9 electrically, so that current entering cup 9 must flow through igniting element 10 in order to reach annulus 8. Mica washer 16 is located between igniting element 10 and eyelet 13 and has a notch 16' for tab 11. Washer 16 prevents igniting element 10 from being short-circuited against washer 12.

The holder 2 is provided with inwardly-bearing spring tongues 17, which hold body 1 in place by friction. Ears 18 serve to make contact with flange 19 of annulus 8 when body 1 is pushed further into holder 2, against the resistance of spring tongues 20. These normally make contact with cup 9, and connect it with a battery

21 through screw 22. Spring tongues 20 are integral with a central plate or collar 20' through which screw 22 passes, held in place on holder 2 by nut 24 and insulating washers 25. The other side of battery 21 is grounded to holder 2 through wire 23'.

The lighter body 1 is provided with an axial passage 26, somewhat larger than a cigarette, except at the inner end, where it is constricted sufficiently, at 27, to hold a cigarette by slight friction, and prevent its being thrown out or dropped inadvertently.

To use the device, a cigarette 28 is inserted, as indicated, with its end against the igniting element 10, and the knob 5 is pushed to the right until ears 18 engage flange 19. This completes the electrical circuit, which is from battery 21 through wire 23, screw 22, springs 20, cup 9, igniting element 10, washer 12, eyelet portion 13, annulus 8, flange 19, ears 18, holder 2, and wire 23' back to battery 21. Upon suitable incandescence of igniting element 10, lighter body 1 is removed from the holder 2 and the exposed end of the cigarette placed between the smoker's lips for lighting by drawing on it in the usual manner without removing it from the lighter body 1. After lighting the cigarette the lighter body 1 is withdrawn from the cigarette and replaced in the holder 2 where it remains until such time as it is required for further use.

Figs. 3 and 4 show different forms of igniting element which may be used instead of element 10 if desired. In Fig. 3 the element 10a has a generally zigzag configuration and in Fig. 4 the element 10b has a generally star-shaped configuration. In both Figs. 3 and 4 the resistance wire is laid out in the form of a pancake as in Fig. 1.

The lighter body 101 shown in Fig. 5 is similar in its essential parts to that of Fig. 1. Holder 102 is enclosed by casing 29, which has a net volume of about four cubic inches. An air-tight seal against the dash 103 is ensured by washer 30, preferably of rubber, and the lighter body 101 is fitted with an air-sealing washer 31, also preferably of rubber, which closes the opening 44 in sleeve 42 when the lighter body 101 is pushed into operating position, so that escaping expanded air from casing 29 must pass through ports 39, past igniting element 110, and out through the constriction 127, and hence through the cigarette 128 therein.

In this form, the contact fingers 120 are shaped so that they will grip cup 109 firmly when the cup 109 is pushed beyond the rounded ends 46. Fingers 120 are made of bimetal and are so disposed that an increase in temperature will cause them to relax their hold on cup 109. Screw 122 supports an extension stud 32, which is insulated from it by the threaded sleeve 33, reinforced by the metal sheath 34. The outer end of stud 32 is threaded, and nut 35 holds the casing 29 in place, being insulated from it by washer 40.

Electrically connected to screw 122 is a terminal 36, and electrically connected to stud 32 is another terminal 37, it being fastened thereto by nuts 41. Between these terminals, and preferably welded thereto, is a heating element 38, which will be seen to be in series with the igniting element 110. Igniting element 110 obviously is of less resistance than that of Fig. 1 for the same battery voltage, since approximately half of the wattage is used in the heating element 38.

The flange 119 is of sufficient diameter to engage inwardly-bearing springs 117, which serve to

make continuous contact therewith, and also hold body 101 by light friction in holder 102. Flanged sleeve 42 engages spring 43 at its inner end, and its outer end bears against the flange 47 of holder 102, making a substantially air-tight seal. Spring 43 bears at its other end against ferrule-like washer 45, which is clamped between knob 105 and insulating cylinder 106 together with washer 31. Constriction 127 prevents air loss and forcible ejection of cigarette 128 when springs 120 release.

To use the form of the device shown in Fig. 5, the cigarette 128 is inserted into the opening 126 until its end engages the igniting element 110 and the knob 105 is pushed in until the maximum diameter of cup 109 passes beyond the ends 46 of fingers 120. The contact fingers 120 being resilient, grip the cup 109 and hold the body 101 against the restoring force of spring 43.

The engagement of cup 109 and fingers 120 completes the electric circuit, causing the igniting element 110 to incandesce. The circuit is as follows: Current from battery 121 passes through wire 123, stud 32, terminal 37, heating element 38, terminal 36, screw 122, fingers 120, to cup 109. Thence the current passes from cup 109 through heating element 110 to annular flange 119 in the same manner as the current passes from cup 9 to annular flange 19 in Fig. 1. The current then passes from annular flange 119 through fingers 117, holder 102 to dashboard 103, thence through wire 123' to battery 121, thus completing the circuit.

Igniting element 110 and heating element 38 incandesce simultaneously and the air in casing 29 is heated and expanded and flows through ports 39 past and through the foraminous igniting element 110 and out through the cigarette 128, lighting the same and forcing smoke through it which appears at the outer end of the cigarette and indicates that the cigarette is lit. At the same time the heat from the igniting element 110 is being absorbed by contact fingers 120 and at the expiration of about 10 seconds the contact fingers, being of bimetal, open, releasing their grip on cup 109 and permitting the spring 43 to return the body 101 to its original position. The abrupt disengagement of cup 109 and the fingers 120 breaks the electric circuit and the snapping out of the body 101 and the indication of smoke shows that the cigarette is lighted.

The cigarette 128 may then be removed from the lighter body without removing the lighter body 101 from holder 102 and the smoker has a lighted cigarette without having to go through the disengaging operation, while driving his car, of manually engaging the outer face of igniting element 110 with the cigarette in his mouth as necessary with conventional lighters of the cordless type.

It is obvious that the casing 29 and the heating element 38 may be omitted in Fig. 5 in which event the lighter body 101 may be removed with the inserted cigarette 128 and the latter placed between the smoker's lips and puffed as explained in connection with Fig. 1 or, if desired, the device of Fig. 5 may be used in a manner similar to the ordinary cordless lighter without inserting the cigarette 128.

As the lighting operation may be performed entirely by touch, since the cigarette is automatically maintained in lighting position, the safety aspect of the invention is obvious, for the driver of an automobile may light a cigarette without fumbling and diversion of attention from the road. In addition, the new construction provides

for increased air flow, as compared with an ordinary lighter. Pipe smokers know that the usual electric lighter plugs the bowl and practically shuts off the draft necessary for combustion, whereas with my new type it is almost as easy to light a pipe as with a match, and in addition there is a tamping action which tends to prevent spilling of burning tobacco. When a cigarette is lighted as described, there is no possibility of particles of burning tobacco falling on the user's clothing, since lighting takes place in the axial hole. If it is desired to snuff a cigarette, placing it in the hole and leaving it for a few seconds, without lighting the lighter, will accomplish this effectively, and the stub then may be thrown away without fire hazard.

Reasonable modifications are intended to be included within the scope of the invention. For example, it is readily conceivable that the thermostatic release mechanism of the form of Fig. 5 may be applied to the form of Fig. 1; or that it may be omitted from the form of Fig. 5. Furthermore, it is obvious that the lighters shown may be adapted to accommodate cigars, in combination with, or instead of, cigarettes. While the ideas disclosed pertain principally to the cordless types of lighters, they are not necessarily thus limited, and it is obvious that the same principles may be applied in those having flexible wire connections, like the earlier forms of automobile lighters.

While it will be found that the form shown in Fig. 1 will often light a cigarette automatically, the action is uncertain, so that if this effect is desired, the positive draft type of Fig. 5 is to be preferred. The method of lighting automatically by means of expanded air is covered by my United States Patent No. 1,983,738, dated December 11, 1934. The draft necessary for automatic lighting also may be produced by other means, such as a piston or a diaphragm. Lighters employing these have been disclosed in my United States patents, Nos. 1,959,093, dated May 15, 1934, and 2,052,016, dated August 25, 1936.

While certain novel features of the invention have been disclosed herein, and are pointed out in the annexed claims, it will be understood that various omissions, substitutions and changes may be made by those skilled in the art without departing from the spirit of the invention.

What I claim is:

1. In a cordless lighter, a stationary support, a lighter body having a knob and adapted to be inserted into said support, said lighter body having an axial passage therethrough, a foraminous planar electric igniting element mounted on said body across the inner end of said passage, the outer end of said passage being flared to facilitate the insertion of a cigarette, whereby said inserted cigarette may be ignited while in said passage from the inner side of said igniting element or a cigar or pipe may be ignited from the outer side of said igniting element after removal from said support.

2. In a cordless lighter, a stationary holder, a lighter body removably mounted in said holder, said body having a passage, a foraminous planar igniting element at the inner end of said passage, the outer end of said passage being adapted to receive a cigarette, whereby said inserted cigarette may be ignited while in said passage from the inner side of said igniting element or a pipe may be ignited and tamped from the outer side of said igniting element after removal from said holder.

3. In a lighter, a body carrying at one end in exposed position an electrically incandescent igniting element, said body having a passage through which a cigarette may be brought into contact with said igniting element, said passage having a constriction fitting said cigarette snugly adjacent to said igniting element, a holder for said body, spring gripping means within said holder for retaining said body portion in a neutral position when placed therein, a source of electric current, contact means to connect said source to said igniting element when said body is inserted in said holder beyond said neutral position, spring return means to return said body to said neutral position when released, a casing associated with said holder in such a manner that the only path of escape of air from within said casing is through the passage in said body when the latter is in said holder, a heating element within said casing, means connecting said heating element so that it is incandescent simultaneously with said igniting element when the latter is connected to said source of current; whereby insertion of said body in said holder to the contact-making position causes incandescence of both elements named, and air in said casing is heated and expanded and forced outwardly through said cigarette, promoting ignition of the same.
4. In a lighter, a body carrying at one end an electrically incandescent igniting element, said body having a passage therethrough communicating with said igniting element and adapted to receive a cigarette with a snug fit and with the cigarette engaging said igniting element, a holder for said body having spring means for maintaining said holder in a neutral position, a source of current, thermostatic contact means adapted to nullify said spring means when the latter are manually overcome by insertion of said body beyond said neutral position to contact-making position, said thermostatic contact means being operable, upon attainment by said igniting element of a predetermined degree of incandescence, to break the circuit and permit said spring means to take effect, a casing associated with said holder and so constructed that the only path of escape of air from within said casing is through the passage in said body when the latter is in said holder in contact-making position, and a heating element in said casing, incandescent simultaneously with said igniting element, whereby air in said casing is heated and expanded and forced outwardly through said cigarette, promoting ignition thereof.
5. In a lighter, a tubular body having a knob on the end thereof and having an axial passage therethrough, a contact cup secured to one end of said tubular body, an igniting element within said cup and located at one end of said passage, the other end of said passage flaring to facilitate the insertion of a cigarette or the like, a tubular holder having contact fingers, said body having contacts frictionally engaging said contact fingers, a sleeve slidable within said holder, said sleeve having an internal shoulder, said body having an external shoulder, a helical spring between said shoulders, said body having a gasket slidable within said sleeve, said tubular holder carrying bimetallic contact fingers adapted to releasably engage the outer surface of said contact cup, a casing surrounding said tubular holder, an electric heater in said casing, whereby when said knob is pressed against said helical spring, said cup and bimetallic fingers engage, causing an

electric current to be supplied to said igniting element and to said heater, said heater causing the air to expand and to flow through said cigarette to light the same and said bimetallic fingers release said cup when heated by said igniting element.

6. In a cordless lighter for cigarettes and the like, a stationary holder well for securing to the body of an automobile or other vehicle, a lighter plug comprising a body having a knob at its outer end, said body being removably located in said holder well, said body and knob having an axial passage therethrough, said passage having a restricted portion to snugly hold an inserted cigarette, an igniting element mounted on said body at the inner end of said passage, the outer end of said passage at said knob being flared to facilitate the insertion of a cigarette, electrical contact devices on said stationary holder well and on said lighter body so arranged that movement of said knob energizes said igniting element whereby an inserted cigarette may be lighted from said igniting element while held in said passage with said plug removed from said holder well, or a pipe may be tamped by the inner end of said body and lighted by said igniting element with said plug removed from said holder well.

7. In a cordless lighter for cigarettes and the like, a stationary holder well for securing to the body of an automobile or other vehicle, a lighter plug removably held in said holder well, said plug having a handle end projecting out from said holder well and a lighting end disposed within said holder well, said plug having a passage therethrough, said passage being of such length and diameter to receive and hold an inserted cigarette, an igniting element mounted on said plug across the lighting end of said passage, axially spaced, forward and rearward electric contacts carried by said lighter plug, said igniting element being connected respectively to said forward and rearward electric contacts by terminal means lying at the sides of said passage in such manner that said igniting element has its outer face accessible to light a cigarette or the like when the lighter plug is removed from said holder well and its inner face accessible to light a cigarette in said passage, said holder well having electric contact means spaced axially thereof for contacting said axially spaced contacts on said lighter plug to supply electric energy to said

igniting element when said plug is held in plugged-in position.

8. In a cordless lighter for cigarettes and the like, a stationary holder for securing to the body of an automobile or other vehicle, a lighter body removably held by said holder, said body having a handle end projecting from said holder and a lighting end, said body having a passage therethrough extending from said handle end to said lighting end, said passage being of such length and cross section to receive and hold an inserted cigarette, an igniting element mounted on said body across the lighting end of said passage so that it is protected when said body is held by said holder, said igniting element having its outer face exposed and accessible to light a cigarette or the like when the lighter body is removed from said holder, the inner face of said igniting element being accessible to light a cigarette inserted in said passage, a yieldable device disposed between said holder and said lighter body urging said lighter body outwardly of said holder, electric contact devices on said holder and on said body engageable by holding said lighter body in pushed-in position against the force of said yieldable device to heat said igniting element, and means for firmly holding a cigarette inserted in said passage to prevent its being thrown out by action of said yieldable device.

9. In a cordless lighter, a stationary holding device having an air-tight wall, a removable plug seating in said holder device, said plug having a handle end projecting from said holder device and a lighting end disposed within said holder device, said plug having air-sealing engagement with said holder device, said plug having at its handle end a cigarette-receiving opening and a cigarette-holding passage extending therethrough adapted to snugly embrace an inserted cigarette and an igniting element at the lighting end of said passage, said holder device having a source of electric energy, controllable means whereby said source of energy may heat said igniter element to incandescence and warm the air trapped in said holder device, whereby the expanded air is forced through said inserted cigarette while in contact with said igniting element to light the inserted cigarette, the outer side of said igniting element being also available to light a cigarette or the like when said plug is removed from said holder device.

LINCOLN K. DAVIS.
